UNITED STATES PATENT OFFICE.

ARTHUR G. GRISWOLD, OF KANKAKEE, ILLINOIS, ASSIGNOR OF ONE-HALF TO J. B. GRISWOLD, OF KANKAKEE, ILLINOIS.

EXPLOSIVE-ENGINE.

No. 872,342.

Specification of Letters Patent.

Patented Dec. 3, 1907.

Application filed September 1, 1906. Serial No. 332,974.

To all whom it may concern:

Be it known that I, ARTHUR G. GRISWOLD, residing at Kankakee, in the county of Kankakee and State of Illinois, have invented a new and Improved Explosive - Engine, of which the following is a specification.

This invention relates generally to improvements in explosive engines, operating under gasoline or other volatile fluids, and particularly to that type of engines in which a single piston acts as the fuel pumping and compressing means, and primarily, my invention seeks to provide an engine of the general type stated, which, compared with similar engines of this type, will be of a simple and economical construction, in which the several parts have a special correlation whereby a maximum explosive power is obtainable from a minimum working charge and in which an explosion is effected at each complete revolution of the crank shaft, of a uniform and timed character, and in which the fuel feed from the carbureter is automatically drawn, in a manner to obtain a desired charge without danger of excess or loss, and in which the explosive charges act as scourers or cleaners for leaving the cylinder in proper shape to receive a new and initially compressed charge.

In its more subordinate nature, my invention has for its object to provide an improved construction of gas engine of the type stated, in which the working cylinder, the working agent feed devices and controlling means therefor, the piston and the exhaust, are correlative so arranged whereby the full return stroke of the piston is utilized for effecting the initial compression of a new charge as it is being forced into the working cylinder in such manner that a positive and effective exhaust or blowing out of the burned residuum is obtained.

In its still more subordinate features, my invention consists in certain details of construction and peculiar combination of parts, all of which will be hereinafter fully explained, pointed out in the appended claims, and illustrated in the accompanying drawings, in which:

Figure 1, is a perspective view of my improved form of explosive engine. Fig. 2, is a vertical section thereof, the piston being at

the beginning of its compressing stroke, the exhaust and intake valves for the working cylinder being closed and the carbureter or working agent feed open. Fig. 3, is a similar view showing the piston at the beginning of its impelled charge compressing position. Fig. 4, is a plan view of the machine. Fig. 5, is a horizontal section thereof, taken on the line 5—5 on Fig. 2.

In the practical application of my invention, I prefer to arrange the same for providing an engine of the "upright" type as shown in the drawings, but I desire it understood that with but slight variations or modifications of the parts shown, my invention may be embodied in an engine of the horizontal pattern.

In the form shown, the engine comprises a closed casing C, in the nature of a cylinder, which has a flange c at the upper end for connecting with the bottom flange b of the working cylinder B, the two cylinders C and B being preferably of like diameter, as shown.

The lower end of the cylinder C has a pendant, centrally disposed semi-circular and narrow extension c' that forms the mate for the semi-circular casing section P which is bolted to the extension c' and together with the said extension c' forms the closed casing for the crank member, of the power transmitting shaft O' journaled in the long sectional hub like bearings o—o integrally formed on and projected from the opposite sides of the crank casing sections C' and P as best seen in Fig. 4, by reference to which it will be also noticed the shaft O' has a balance wheel R at one end and a gear 1 on the same end, the purpose of which will be presently explained, the other end, in practice, having the transmitting sprocket or pulley, not shown.

M designates a cross head slidably mounted in the casing C, connected by the rod N with the crank shaft O, and joined to the rod a of the working piston A, said rod passing through the gland or stuffing box S. So there can be no vacuum either in the crank casing or the cross head casing C, the cross head has apertures V that maintain communication between the crank and the cross head casings at all times.

The working cylinder B has a port in its

upper end that communicates with a supplemental fluid compressing chamber or hollow head T with which communicates a charging chamber in the nature of a tube G, 5 located adjacent to, but not in touch with the cylinder B, and which extends down to the bottom of the said cylinder B, its lower end being open to receive a tubular valve casing f, threaded into the said lower end of 10 tube G, provided with a feed inlet at one side that communicates with the aperture g in tube G that received the end of the delivery pipe d from the carburetor or working agent feed device D, which pipe d has a back 15 check valve d', the reason for which will presently appear. The valve casing f also has a port f² that registers with an aperture g' in the tube G and with a large port b⁴ that leads to the bottom of the working cylinder 20 B, and at the upper end the casing f has a foot valve F normally held down to close off the said casing by a spring f³, suitably sustained within the casing f, as shown.

H designates a valve for coöperating with 25 the inlet to the cylinder B and which is arranged to open inwardly, and is normally forced to a closure position by the spring K mounted about the upper end of the valve stem h and under a tripper device I, in the 30 nature of a walking beam fulcrumed in the bracket i on the top of the working cylinder whose outer end is pivotally connected to a rod J, guided in the upper and lower brackets j' and having its lower end bifurcated to 35 receive the roller bearing j² held to engage a cam L on a cam shaft Z mounted transversely of the machine in the brackets Z'-Z' as clearly shown in the drawings, to which continuous motion is given by the gear 3 40 thereon, which meshes with an idler gear 2, that engages the gear 1 on the power or crank shaft.

The working piston A is of suitable thickness and has the usual packing rings, and the 45 stroke of the piston is so regulated as to provide for a maximum compression of the initially compressed charge when it reaches the limit of its upward stroke, and for effecting a maximum initial compression to 50 the new charge on its forward or impelled stroke before it fully uncovers the exhaust, so that, when the exhaust is opened, the new charge will, by reason of its initial compression, completely scour or free the working cylinder of the burned residuum and fill 55 it with a new and pure charge of working agent before the piston begins the back or final compression movement.

The exhaust port E is at times shut off by 60 a spring closed valve Q, mounted on a lift rod or stem q, located outside the casing C and guided in a bracket j', its lower end being bifurcated to receive a friction roller q²

held to be engaged by a cam Z⁵ on the cam shaft l, as shown.

R designates a cap plate for closing the man hole r in the casing C. The working cylinder is water jacketed in the usual manner, as shown.

By reason of the peculiar arrangement and 70 coöperative combination of the several parts as described and shown, a compact, simple and stable construction of engine is provided and in which the crank shaft is so held with respect to the cross head and the working 75 cylinder that a direct action of the operating parts is obtainable and simple means provided for accurately, and at proper predetermined times, actuating the valve lift rods for the cylinder inlet and exhaust ports.

The advantages of my engine, it is believed, will be readily apparent to those skilled in the art, from the foregoing description when taken in connection with the accompanying drawings.

Assuming the parts to be now in the position shown in Fig. 2, the piston is now traveling on the beginning of its return or upward thrust. During the said adjustment and travel of the piston, the inlet valve H and 90 exhaust valve E are held closed by reason of the cams now being disengaged from their lift rods and the compression of the charge being now effected in the explosion end of the working cylinder, the valve d' of the carburetor is now open and the feed valve is held closed which provides for taking in a new charge of the working agent from the carburetor and to the back of the piston. When the crank, which is now traveling in 100 the direction of the arrow 10 on Fig. 2, just begins to pass the center, an explosion of the highly compressed charge in the cylinder is now effected in any well-known manner, which forces the piston to the return stroke 105 as indicated by the arrow on Fig. 3. During this movement, the working charge which was turned in back of the piston on the upstroke, is initially compressed and forced past the valve F, which is now open, into the tube G and the supplemental chamber T, the valves Q and d' being now held closed by the partial compression of the new working charge and the valve H held closed by the unexpended pressure of the exploded charge 110 in the cylinder. As the piston descends the 115 rod j to open the valve H just after the piston begins to uncover the exhaust port E, whereby the said valve will open immediately after the initially compressed charge enters the cylinder so as to force out all the residuum or burned mixture within the said cylinder, it being obvious that the valve F 120 when held down by suction on the up stroke

125

of the piston B, closes off the tube G from the cylinder and also from the fuel feeding carbureter device, it being also apparent by referring to Figs. 2 and 3 that when the piston B begins its up thrust, the cams that trip the valves Q and H will disengage the actuating rods for the said valves, while the final compressions of the initially compressed charge within the cylinder A will now assist the springs and hold the valves closed, while at the same time the suction caused by the up stroke of the piston draws in a new charge, it being understood that the compressed charge in front of the piston is fired by any suitable electrical or mechanical sparking device controlled by the movement of the machine.

While I have described the movement of the piston up and down, it is understood that such movement, will also mean a "to and fro" stroke of the piston in whatever position it may be set for operation whether in an upright, horizontal or other character of engine.

Having thus described my invention, what I claim and desire to secure by Letters Patent, is:—

1. The combination of a casing, a crank shaft mounted therein, a working cylinder and piston therefor, a second casing connected at one end of the working cylinder and having communication with the crank casing, the two casings and the working cylinder being in longitudinal alinement, a cross head for the crank shaft, movable in the second casing, said cross head having a rigid rod connection with the piston, valve controlled exhausts and inlets for the working cylinder, a supplemental fluid compression chamber that discharges through the working cylinder inlet and communicates with that end of the cylinder opposite the inlet thereof, a valved working agent feed that discharges into the supplemental compression chamber, a foot valve in the said supplemental chamber that discharges automatically and closes as a new charge is being drawn into the cylinder and means for controlling the inlet and exhaust valves at predetermined times.

2. The combination with a working cylinder having a valved inlet and a valved exhaust; of a supplemental compression chamber that discharges at one end through a valved inlet of the working cylinder and has the other end in communication with the other end of the working cylinder, a back check valve in the said other end of the supplemental compression chamber, a working piston, a crank shaft and mechanical devices actuated by the crank shaft for controlling the exhaust and inlet valve for the working cylinder at predetermined times.

3. In an explosive engine of the character described, the combination with a working cylinder, a piston and an automatically controlled valve exhaust and inlet port for the cylinder, a supplemental compression chamber that communicates at one end through the inlet of the working cylinder, the other end of the said compression chamber having communication through the opposite end of the working cylinder, a valve operating under suction for cutting off the supplemental compression chamber as a new charge is being brought into the back of the piston and a fuel feed having a back pressure valve that discharges into the supplemental compression chamber at a point between the valve and the discharge of the lower or back end of the working cylinder, all being arranged substantially as shown.

4. In an explosive engine of the character described, the combination with the working cylinder and piston, said working cylinder having an automatic valve controlled exhaust port and an automatic valve controlled exhaust in one end thereof, the other end having a fuel intake; of a supplemental or charging chamber in communication with the fuel inlet of the cylinder, a working agent valve feed or carbureter that discharges through the charging chamber and into the fuel intake for the cylinder on the return stroke of the piston, said supplemental chamber being located outside of the working cylinder, and a valve in said cylinder at a point near the point of its inlet, all being arranged substantially as shown and described.

5. In an explosive engine of the character described, the supplemental or charging chamber that discharges through the valved inlet of the working cylinder and has communication with the fuel intake for the cylinder, a carbureter connected to the lower end of the said charging chamber, a tubular member detachably fitted in the lower end of the charging chamber and a foot valve on said tubular member, all being arranged substantially as shown and described.

6. In a gas engine of the character described, the combination with the working cylinder having a supplemental or dome-shaped portion at one end, an inlet connecting said dome portion to the cylinder, an automatically controlled valve for the said inlet, an exhaust for the cylinder, an automatically controlled valve for said exhaust, the controlling means for the inlet valve comprising a walking beam and a vertically adjustable shifting rod connected thereto, actuating devices for the exhaust valve including a lifting rod, a crank shaft and piston, a transversely disposed shaft having cams for engaging the lifting rods of the valve actuating devices, gearing connecting said

shaft with the crank shaft, a working agent feed pipe, a charging chamber exterior of the working cylinder that communicates at one end with the dome portion of the cylinder and at the other end with the opposite end of the cylinder, said working agent feed being connected with the charging chamber at a point in line with its communication with

the cylinder, a check valve for the working agent feed and a foot valve in the charging chamber, all being arranged substantially as shown and described.
